(57) **CLAIM**

The ornamental design for a laser machine with closed door, as shown and described.

DESCRIPTION

FIG. 1 is a front right side perspective view of a laser machine with closed door showing my new design;

FIG. 2 is a front elevation view thereof;

FIG. 3 is a rear elevation view thereof;

FIG. 4 is a left elevation view thereof;

FIG. 5 is a right elevation view thereof; and,

FIG. 6 is a top plan view thereof.

The broken lines in the drawings depict unclaimed environmental subject matter.
